UNITED STATES PATENT OFFICE.

THOMAS J. MAGNER, OF HORNELLSVILLE, NEW YORK.

TORSION-SPRING FOR VEHICLES.

SPECIFICATION forming part of Letters Patent No. 239,178, dated March 22, 1881.

Application filed January 13, 1881. (Model.)

To all whom it may concern:

Be it known that I, THOMAS J. MAGNER, a citizen of the United States, resident at Hornellsburg, in the county of Steuben and State of New York, have invented certain new and useful Improvements in Torsion-Springs; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification, in which—

15 Figure 1 is a cross-section. Fig. 2 is a partial longitudinal section. Fig. 3 is a plan view from below. Figs. 4, 5, and 6 are detail sections.

This invention relates to torsion-springs, especially their adaptation to side-bar vehicles.

20 The invention consists in the construction hereinafter described, and particularly pointed out in the claim.

In the drawings hereto annexed, A is the head-block, B the rear axle, and C C the side bars, of a vehicle, all connected together by 25 the clips D. At the point of connection the side bars are cut out transversely at e, and the head-block and rear axle at a.

E are metal blocks having raised portion d 30 and perforated ends e. These blocks are placed between the ends of the side bars and head-block and rear axle, with raised portion d resting in, and snugly fitting in, groove e, and the lower portion with ends e in grooves a, and the 35 sides of clips D passing through perforations e.

F is a torsion spring or bar, having its ends f f firmly held in plates E, there being one spring to each side bar, running under the same and held tightly at the middle by a clip, 40 G, in whose plate g the spring is firmly fastened. Midway between this clip G and the ends of the spring is located a clip, H, in the plate h of which is the circular bearing h', the spring passing through such plate and being 45 rounded in said circular bearing. Rigidly se-

cured to spring F, upon each side of this plate h, is an arm, k, of hanger K, to whose outer ends, by bolt l, is attached a semi-elliptic body-supporting spring, L.

By this construction the spring F is formed 50 into four torsion-springs, two for each semi-elliptic spring, and forms a spring-platform, which furnishes a high degree of elasticity and produces an easy-riding vehicle.

By way of modification, the spring F may 55 be made in two pieces, their meeting ends being held by clip G; or two smaller clips may take the place of this single clip, one for each end.

As another modification, the spring F may 60 be cut away just beyond the arm k of hanger K, which is the farthest from the head-block or rear axle, which construction only gives four torsion-springs to the vehicle, or two to each side bar.

65 Torsion side springs having cranks at their outer ends, fixed at their inner ends to central clips upon the under faces of the side bars, and supported near their outer ends by clips, have been used in connection with semi-elliptic 70 springs, and protection is only asked for the specific construction hereinafter claimed.

What I claim is—

As an improvement in side torsion-springs for vehicles, the torsion-springs F F, having 75 their ends fixed to the plates E E of the clips D D, and tightly held at their middles by the clips G G, and provided with the arms k k, composing hanger K, in combination with clips H, having bearings h' in their plates h, and the 80 semi-elliptic springs L L, constructed and operating substantially as and for the purposes set forth.

In testimony whereof I affix my signature in presence of two witnesses.

THOMAS J. MAGNER.
